UNITED STATES PATENT OFFICE.

WALLACE K. WILEY, OF BUFFALO, NEW YORK; ASSIGNOR TO FLEXLUME CORPORATION, OF TONAWANDA, NEW YORK, A CORPORATION OF NEW YORK.

ELECTRIC SIGN.

Application filed January 26, 1924. Serial No. 638,835.

This invention relates to improvements in electric signs of the type in which translucent letters or characters provided upon one or more faces of a box-like casing are illuminated by electric lamps enclosed within such casing.

In this type of electric sign, the display faces may be of various constructions. As intended for outdoor illumination they are usually formed of metal and provided with openings in the outline of the letters or characters to be displayed, the openings being backed by glass plates which are removably secured and which may be either flat throughout their extent or provided with letter strokes or characters in relief to project through the openings.

In such signs normally closed openings or "windows" are provided in the frame walls, that is to say, the walls at angles to the display face or faces, by which access may be had to the interior of the sign for the purposes of substituting electric lamps, cleaning the glass letter plates, or substituting new plates for broken ones. Such windows have heretofore been closed by flat plates. These have been fitted more or less lightly against the frame walls in which the windows are formed, the object being to make the sign light proof and weather proof. The sign box being otherwise closed, there has been no certain provision for ventilating its interior to counteract the heat developed by the electric lamps which in most cases are, or should be, of high power. The presence of the windows also has a weakening effect on the wall in which the windows are formed, whereby such wall will sag or be wavy, particularly if it be an upper wall. This weakening of the wall is intrinsically objectionable and frequently results in crevices around the edges of the windows, i. e. between the walls and the window closure plates, through which rain or snow water may pass into the sign with undesirable effects and through which light may escape.

The present invention relates particularly to novel co-operating structural features of the windows and their closures and has for its object to provide a simple structure by which the interior of the sign will be adequately ventilated, a light proof and weather proof closure of the windows will be effected,

the frame walls will be reinforced so as to avoid sagging and a further advantage in accessibility will be served.

The invention is illustrated in the accompanying drawing, wherein:

Figure 1 is a plan view of the structure in connection with the upper wall or a vertical wall of the sign box.

Figure 2 is a side view of the same, the wall being shown in section.

Figure 3 is a section on the line 3—3 of Figure 1.

Figure 4 is a bottom plan view of the structure in connection with the lower wall of the box.

Figure 5 is a side view of the same, the wall being shown in section.

Figure 6 is a section on the line 6—6, of Figure 4.

The frame wall is shown at F and is provided, according to its length, with one or more openings or hand holes 1 through which ready access may be had to the interior of the sign box for such purposes as may be required. Each opening 1 is bounded by a marginal flange 2 which projects outward from the wall F, preferably at a right angle thereto. The opening 1 is normally closed by a cover which consists of a flat plate 3 overlying said opening and provided with a marginal flange 4 which extends at a suitable angle to said plate and bears against the wall F. The plate 3 conforms in outline to but is of greater area than the opening 1 and the flange 4 is of greater depth than the flange 2 and thereby a passage 5 of sensible dimensions is provided for between the flanges 2 and 4 and between the flange 2 and the plate 3. The passage 5 communicates with ventilating openings 6 in the flange 4, the openings preferably being formed as recesses in the bearing edge of said flange. The cover is suitably attached to the wall F and for this purpose may be provided at its ends with lugs 7 which project from the flange 4 and are engaged by catches 8 pivotally mounted on the wall F.

The cover shown in Figures 4 to 6 in addition to the features above described is provided in the plate 3 with a drainage opening 9 over which is arranged a light shield 10 in the form of a channel open at its ends.

The flange 2 serves several purposes; thus it reinforces the wall F against the weakening effect of the opening 1, thereby preventing said wall from sagging; it overlaps the opening 6, thereby, in connection with the plate 3, preventing the escape of light from the sign box; and it forms a barrier against the passage of water into the sign box. In addition said flange co-operates with the cover plate 3 and its flange 4 to provide a passage through which air may freely pass into and from the sign box.

At the upper side of the sign box any water which may accumulate due to rain or to the melting of snow will drain from the ends of the box before it rises to the level of the upper edge of the flange 2. Along the vertical frame walls practically all water will be diverted by the flange 4 and such negligible amounts as may find entry through the openings 6 will escape through the drainage openings 9 of the bottom closures 3. Since the closure plates bear upon the frame walls merely along the edges of the flanges 4, there are no overlapping bearing areas of substantial dimensions which, due to rusting or freezing, might interfere with the ready removal of the clo-

sures 3 when it is desired to expose the openings 1.

It is of course apparent that minor modifications may be resorted to without departing from the essential features of the invention.

Having fully described my invention, I claim:

In an electric sign of the enclosed lamp type a frame wall having a hand hole to give access to the interior of the sign for the purpose of the removal or substitution of enclosed parts thereof, in combination with a marginal flange projecting outward from said hand hole, a cover comprising a plate substantially conforming in outline to but of greater area than said hand hole and arranged to overlie the same and a marginal flange projecting from said plate toward said frame wall, said flanges being formed to provide an air passage in communication with said hand hole and with the exterior of the sign, and means for securing said cover to said frame wall whereby said cover may be moved to expose said hand holes.

In testimony whereof I affix my signature.

WALLACE K. WILEY.
